UNITED STATES PATENT OFFICE.

WILLIAM MILLS, OF DANESBURY, SOLIHULL, ENGLAND.

DESIGN FOR A HEAD OF GOLF-CLUBS.

43,885.

Specification for Design.

Patented Apr. 22, 1913.

Application filed July 20, 1912. Serial No. 710,711. Term of patent 7 years.

To all whom it may concern:

Be it known that I, WILLIAM MILLS, a subject of the Kingdom of Great Britain, residing at Danesbury, Alderbrook Road, Solihull, in the county of Warwick, England, have invented a new, original, and ornamental Design for the Head of a Golf-Club, of which the following is a specification, reference being had to the accompanying drawing, forming part thereof.

Figure 1 is a perspective view of the head and Fig. 2 is a plan view of the head of a golf club showing my new design.

I claim:—

The ornamental design for the head of a golf club as shown.

WILLIAM MILLS.
